UNITED STATES PATENT OFFICE

FRANK X. LAUTERBUR AND EDWARD J. LAUTERBUR, OF SIDNEY, OHIO

FUEL SUPPORTING DEVICE FOR FURNACES

Application filed March 22, 1930. Serial No. 438,111.

Our invention relates to furnace grate bar or fuel support construction, and especially to a novel construction which enables adjustment of the sizes of the openings between the 5 grate bars or fuel supports to allow for burning different types of fuel.

In grate bar or fuel support construction for furnaces, there have been a number of types which are particularly efficient for 10 burning different types of fuel. For example, if Pocahontas coal is to be burned there are a number of types of grate bars which will enable this type of coal to be burned with a minimum of ash loss. Other 15 types of grate bars have been designed for burning efficiently anthracite coal. Other types have been designed for slack coal.

To the best of our knowledge and belief, 20 however, there has never been designed for a household or apartment house furnace a grate bar or furnace fuel support which could be adjusted to various sizes of ash openings which could be adjusted at will so that 25 no matter what the type of fuel sought to be burned, the ash could be handled efficiently.

It is the object of our invention to provide 30 a grate bar or fuel support construction, in which there is an upper fuel supporting assembly with apertures extending therethrough, and to provide a lower assembly 35 movable relatively to the upper structure and with supporting members adapted to fit into the apertures in the upper assembly. It is a further object of our invention in such a combination of upper and lower fuel supporting assemblies to introduce a forced draft either through the lower grate bar assembly in case the fuel requires it, or in some other suitable manner.

40 The above and other mechanical improvements in fuel supporting construction we accomplish by that certain combination and arrangement of parts of which we have shown several preferred modifications.

45 Referring to the drawings:—

Figure 1 is a diagrammatic view of a furnace equipped with fuel supports movable so as to vary the ash space between the bars 50 for handling different types of fuels.

55 Figure 2 is a diagrammatic view showing

different possible spacings of the upper and lower fuel supporting assemblies, the bars being indicated in side elevation.

Figure 3 is a plan view of a fuel supporting assembly such as is indicated in the other 55 figures.

Figures 4 to 7 show various modifications of different types of upper and lower assemblies.

Figure 8 is a diagrammatic view showing Figure 3 in side elevation provided with 60 means for rocking the solid grates.

Figure 9 is a diagrammatic side view of a motor driven device for lowering the lower grates shown in Figure 1.

Figure 10 is a diagrammatic side view of 65 a manual shifter bar effective on lower fuel supporting assemblies such as are shown in Figure 1.

Figure 11 is a plan view showing more in detail, a manually actuated device for mechanically raising and lowering the lower 70 assemblies.

Figure 12 is a side elevation of the mechanism shown in Figure 11.

Referring to Figure 1, the ash pit of the 75 furnace is indicated at 1, the fire pot being indicated at 2. The upper assembly consists of a series of solid bars 3 extending across the fire pot. These bars have wings 4 projecting therefrom and are spaced with openings 5 so that the mounting supports 6 of the bars will extend through the furnace wall so that the assembly may be shaken in the usual manner exteriorly of the furnace as indicated by the shaker bars 6a in Figure 8 attached to the 80 ends 6b of the supports 6. The lower assembly which is movable to and from the upper assembly, and, as shown in various modifications in Figures 1, 8 and 9, consists of a hollow 85 tubular structure having a main supporting pipe 7, through which an air blast may be introduced into the interior of the tubes. There are branch tubular members 8 extending up to pipes 9 which extend across the furnace and on which hollow supports 10 are 90 mounted. The hollow supports 10 have a series of discharge apertures 11 through which an air blast may be introduced through the pipe 7 up through the supporting pipes 8 and out through the discharge passages in the 95

100

supports, being directed upwardly through the openings 11 formed between the extending arms 4 of the upper assembly. In Figures 1, 7 and 8 we have indicated in dotted 5 lines the lower movable assembly moved downwardly to the bottom of the furnace. Figure 9 shows a motor 12 with an eccentric strap 13 actuating an eccentric 14 which moves the arm or pipe 15. This may be accomplished by a simple lever mechanism, as shown in Figure 10, from the outside of the furnace. We may pivotally mount the bars 10 as indicated at 9a so that when they are removed from the upper assembly they may be 10 pivoted down to the position indicated at 10a. In Figure 10 a lever 16 pivoted at 17 on a boss on the furnace is connected to the branch pipes 8a.

With a fuel support construction such as 20 we have suggested, it will be possible to vary the ash opening between the bars by adjusting the position of the lower assembly. Thus, in Figure 2 we have shown diagrammatically in the upper figure the bars completely closing the opening in the upper assembly. In the figures below the upper figure, various different spacings of bars are shown. In Figures 4 to 7 we have shown 25 various arrangements for mounting and assembling the lower fuel supporting assembly to suit different designs of furnaces. Thus, in Figure 4 we have shown the upper assembly 3a with the lower assembly 10b mounted on tubular members 9b extending from a central branch pipe 7b. In Figure 5 we have shown the upper assembly 3b with hollow bars 10c extending on spider-like tubular members 8c from a central supporting point 30 7c.

40 In Figure 6 we have shown the upper assembly 3c with a lower assembly comprising bars 10d mounted on a tubular casting 8d and supported by a central tubular member 7d.

45 Figure 7 shows the combination of an upper assembly 3d with a lower assembly consisting of bars 10e pivoted on pipes 9e, same being supported by a central air blast conduit 7e. We have shown different spacings between the upper and lower assemblies in Figures 4 to 7 to indicate different spacings which 50 may readily be obtained.

In Figures 11 and 12 we have shown a furnace having an upper assembly 3e with a lower assembly 10f consisting of a plurality of tubular members mounted on a frame 18. A blower 19 is shown operated by a motor 20. A tubular member 15a supplies air to be forced through the fuel. In the modification 60 shown the forced draft is introduced into the branch conduits 7f from which it passes to the hollow lower assembly fuel supporting members. The members 10f may be shaken as by shaker levers 21 which extend outside 65 the furnace and may be manually operated.

A manually operated wheel 22 carries on its shaft 23 a worm drive 24 which engages a worm gear 25. The support 18 is threaded at 26, and, as will be obvious, when the gears 25 are rotated the threaded shaft 27 will be turned thereby lowering the supports 18. Chains 28 extending from sprockets 29 mounted on the shaft 23 rotate worm driving gears 30 which rotate the shafts 31, 32 so that the supports 18 will be lowered evenly.

At any desired position the members 10f of the lower assembly may be rocked by the levers 21 so that any ashes carried on them may be dumped.

It will further be entirely feasible to introduce a forced draft through members of the upper assembly.

In use the householder purchases whatever type of fuel he desires to burn. If he desires a large fuel supporting area he spaces the lower assembly a considerable distance from the upper. If he is burning a very fine fuel requiring small apertures in the fuel supporting area, he moves the lower assembly to a more elevated position. Further, a certain air blast through the hollow bars when the lower assembly is spaced a considerable distance from the upper assembly will result in a different draft on the fuel than if the lower grate bar assembly is substantially filling the openings in the upper assembly.

Thus the various adjustable positions of the lower grate bar assembly relative to the upper provide an inexpensive construction which will permit the efficient burning of substantially any desired type of fuel.

Having thus described our invention, what we claim as new and desire to secure by Letters Patent, is:—

1. In a furnace grate bar construction the combination of an upper assembly of solid grate bars having ash openings therein and a lower assembly of grate bars mounted for movement into and away from the ash openings in the upper grate bar assembly and means for introducing an air blast through said lower grate bar assembly, the grate bars in the lower assembly being hollow and having openings therein through which the air blast may be directed upwardly into the openings in the upper assembly.

2. In combination with a furnace, a fuel supporting assembly comprising an upper assembly of members having openings therebetween and a lower assembly of members having portions movable into position to vary the clearance provided through the openings between the upper assembly, the members in said lower assembly being pivotally mounted on tubular supports through which an air blast from a source of supply may be provided.

3. A grate bar assembly for a furnace having upper grate bar members with projecting wings constructed and arranged and so

spaced as to provide ash openings, said assembly having lower members carrying grate bars extendible into the openings in the upper grate bar members and removable therefrom to vary the size of the ash opening provided by said assembly, said lower assembly comprising hollow grate bars mounted on tubular members through which an air blast may be introduced into the grate bars of the lower members.
